UNITED STATES PATENT OFFICE

JAMES P. BURKE, OF WAYNE, NEW JERSEY, ASSIGNOR TO MACK MOLDING CO., OF WAYNE, NEW JERSEY, A CORPORATION OF NEW JERSEY

CLOSURE FOR CONTAINERS

Application filed February 17, 1931. Serial No. 516,443.

This invention relates to closures for containers and it is an object of this invention to provide a closure means or cap which is attached to the container so that it can not be separated therefrom and which can be operated to open the discharge orifice of the container without detaching the cap from the container. It is also an object of this invention to provide a closure means or cap having a discharge orifice therethrough which can be readily operated to align its discharge opening with the opening in the container, or to close the opening in the container without detaching the cap from the container and which is brought into close contact with the container to provide a perfect seal therefor when operated to close the opening in the container so as to prevent evaporation or contamination of the contents of the container.

In the drawing—

Figure 1 is a central vertical section of a portion of a container provided with a closure constructed in accordance with this invention, the parts being shown in closed position and with the retaining flange of the container in position to permit application of the cap.

Figure 2 is a view similar to Figure 1 showing the closure in open position and the retaining flange of the container bent over to retain the cap.

Figure 3 is a view similar to Figure 2 of a modified construction.

Figures 4, 5 and 6 are horizontal sections taken on lines A—A, B—B and C—C, Figures 1, 2 and 3 respectively.

Figure 7 is a view in elevation of a portion of a container with a closure device constructed in accordance with this invention.

Figure 8 is a top plan view of the container of Figure 7 without the closure device and with the retaining flange as shown in Figure 1.

Figure 9 is a bottom plan view of the closure device or cap of Figures 1 and 2 shown removed from the container.

Figure 10 is an inverted central vertical section of the cap taken as on the line D—D of Figure 9; and

Figure 11 is a view partly in vertical sec-

tion and partly in elevation of a further modification.

In the drawing the invention is shown applied to a container 1 of the collapsible tube type, the cylindrical body of which merges into a conical portion 7 which ends in a cylindrical or neck portion 14, the outer end of which is closed by a wall 15 in which there is an opening or discharge orifice 10. The conical portion 7 is formed with a flange 6 spaced from the neck portion 14 and projecting from the base of the neck portion 14 is a lug or stop 11 (see Figure 8).

The cap 5 comprises a hollow cylindrical body closed at one end by a wall 13 and having an outwardly projecting flange 12 at its other end. The wall 13 is provided with a discharge opening 9 and the inner face of the wall 13 opposite the discharge opening 9 is recessed to receive a liner or gasket 8 which projects slightly beyond the inner face of the wall 13. The inner edge of the cap at the flange 12 is recessed as at 16, in Figure 9, to provide shoulders 16a and 16b which cooperate with the stop 11 and limit the turning movement of the cap 5 on the neck 14. The recess 16 is so positioned on the cap 5 with respect to the opening 9 that, with the cap turned to its limit in one direction, the liner 8 will be presented to the opening 10 while, when the cap 5 is turned to its limit in the opposite direction, the opening 9 will align with the opening 10 in the wall 15 of the container. The length of the recess 16 is sufficient to permit of substantially a half turn of the cap.

When formed the flange 6 is left projecting, as shown in Figure 1, but after the cap 5 is applied to the container the flange 6 is bent over, as shown in Figure 2, to engage with the flange 12 of the cap 5 and to bear slightly against the flange 12 so as to afford some frictional resistance to the turning movement of the cap 5 on the neck 14 and to cause the seal or liner 8 to bear with moderate pressure on the wall 15.

In the construction shown in Figure 3 the container 1 has the conical portion 7 and a neck 14' which is closed at its outer end by a wall 15' having a central discharge opening

10' which is surrounded by an outwardly projecting flange 24. The conical portion 7 of the container has a flange 6' which is bent over to engage with the flange 12' of the cap 5' to retain the cap on the container. 5 The cap 5' has a discharge opening 9' in its outer wall 13', the opening 9' being eccentrically disposed in the wall 13'. Extending inwardly from the wall 13' at the center thereof is a projection 23 which cooperates 10 with the opening 10' in the outer wall 15' of the neck 14'. The central portion of the outer wall 13' of the cap 5' is recessed so as to form a substantially cylindrical shoulder 25 which engages with the outer face of the flange 24 of the neck 14'. The cap 5' is 15 interiorly threaded as at 18 to engage with threads formed on the neck 14'.

The inner edges of the cap 5' and flange 6' are provided with a stop 22 which cooperates with a stop 21 (see Figure 11) formed on the container 1 between the neck 14' and the flange 6'. The slope to the upper surface of the stop 21 and the corresponding slope on the stop 22 correspond with the slope 25 of the threads on the cap. In this construction the flange 6' will limit the outward movement of the cap 5' but sufficient lost motion is provided between the flange 12' and the flange 6' to permit of the withdrawal of the 30 projection 23 from the opening 10' so that the cap will be spaced outwardly a slight distance from the outer wall 15' of the neck 14' and the contents of the container may be 35 discharged through the opening 10' and the opening 9'.

In closing the container the rotation of the cap 5' causes the cap to be drawn down on the neck 14' forcing the projection 23 into 40 the opening 10' until the engagement of the stops 21 and 22 prevent further rotation of the cap 5' on the neck 14' of the container.

In the modified construction shown in Figure 11, the neck of the container and the cap 45 5" are threaded as in Figure 3 and stops 21 and 22 are provided, as in that construction. The cap 5" is provided with an opening 9 and a liner or seal 8 as in the construction shown in Figure 1, which opening and seal 50 cooperate with an opening 10 similar to the opening 10 of Figure 1 in the outer wall 15 of the neck of the container. In this construction as in the construction of Figure 3, a sufficient lost motion is provided between 55 the flange 12" of the cap 5" and flange 6" of the container to permit the cap 5" to make a half turn in order to bring the opening 9 or the liner 8 into register with the opening 60 10 of the container. When the opening 9 registers with the opening 10, the cap 5" is spaced a short distance outwardly from the outer wall of the neck of the container but when the liner 8 registers with the opening 65 10 the liner 8 contacts with the outer wall

of the neck of the container so as to provide a perfect seal for the container.

What I claim is:—

1. In combination with a container having a cylindrical neck with a wall perforated 70 eccentrically at the outer end thereof and a circular flange surrounding the inner end of said neck and spaced therefrom, a cap having a flat outer wall with a discharge orifice therein eccentrically disposed for cooperation with the opening in the container wall and a circular side wall projecting from said top wall and surrounding said neck, said circular side wall having an outwardly projecting flange at its free edge engaging beneath 80 the circular flange on the container.

2. In combination with a container having a cylindrical neck with a wall perforated 85 eccentrically at the outer end thereof and a circular flange surrounding the inner end of said neck and spaced therefrom, a cap having a flat top wall with an eccentrically disposed discharge orifice therein and an eccentrically disposed inwardly projecting sealing member, said orifice and sealing member alternately cooperating with the opening in the container wall, and a circular side wall projecting from said top wall and surrounding said neck, said circular side wall having an outwardly projecting flange at the free edge 95 thereof, and the circular flange on the container cooperating with the outwardly projecting flange on the cap to retain the cap on the container while permitting rotation of the cap.

3. In a container having a body with a neck formed with a discharge orifice therein, a flange for interlocking with a rotatable container closure surrounding the inner end of said neck and spaced therefrom and a projection forming a stop for a container closure intermediate said flange and neck.

In testimony whereof I have signed my name to this specification.
